UNITED STATES PATENT OFFICE

2,179,483

MATERIAL SPREADER

Francis E. Curriwan and Carl W. Brown,
Brattleboro, Vt.

Application February 1, 1939, Serial No. 254,121

3 Claims. (Cl. 275—8)

The present invention relates to new and useful improvements in material spreaders of the type adapted to be mounted beneath the rear end of a truck body and including a rotating spreading disk driven by a ground engaging wheel.

The primary object of the invention is to provide, in a manner as hereinafter set forth, a material spreader of the aforementioned character embodying a novel construction, combination and arrangement of parts through the medium of which the device may be expeditiously adjusted as desired for operation on trucks of different heights.

Another very important object of the invention is to provide a material spreader of the character set forth embodying novel means for frictionally driving the spreading disk from the ground engaging wheel.

Still another important object of the invention is to provide unique means through the medium of which the width of the area over which the material is spread may be controlled as desired.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a material spreader constructed in accordance with the present invention, showing the device attached to the rear end of a truck and ready for operation.

Figure 2 is a view in front elevation of the machine.

Figure 3 is a bottom plan view of the device.

Figure 4 is a vertical sectional view through an intermediate portion of the invention.

Figure 5 is a top plan view of the intermediate portion of the device.

Figure 6 is a perspective view of an end portion of one of the side members of the frame.

Figure 7 is a detail view in vertical section through the rotating spreader disk, showing the comparatively high and low vanes or ribs thereon.

Referring now to the drawings in detail, it will be seen that the embodiment of the invention which has been illustrated comprises an elongated hopper of suitable material which is designated generally by the reference numeral 1. The hopper 1 is adapted to be mounted transversely beneath the rear end of a truck body 2 by suitable means, such as adjustable hook equipped chains 3. It will be noted that the truck body 2 is shown

in its inclined position for dumping and the end gate 4 thereof is open.

The bottom of the hopper 1 comprises inclined side portions 5 and a horizontal intermediate portion 6. The horizontal intermediate portion 6 of the bottom of the hopper 1 has formed therein a discharge opening 7. The opening 7 is controlled through the medium of slidable plates 8 which are operated by hand levers 9. This is shown to advantage in Fig. 4 of the drawings.

Mounted beneath the hopper 1 is a frame structure which is designated generally by the reference numeral 10. The frame 10 includes a pair of spaced, parallel side bars 11 having mounted thereon guides 12. Connecting the forward ends of the side bars 11 is a cross member 13. Extending between the side bars 11 at an intermediate point is a shaft 14 having mounted thereon spaced, pneumatic tire equipped wheels 15. It may be well to here state that the wheels 15 are adapted to engage the ground for actuation thereby when the machine is in operation.

The frame 10 is connected to the hopper 1 for vertical adjustment relative thereto through the medium of a lazy tong device which is designated generally by the reference numeral 16. The lazy tong device 16 includes pairs of angular, crossed metallic bars 17 and 18 having their upper ends pivotally secured beneath the hopper 1. The lower ends of the bars 18 are journalled on the shaft 14. Pivotally mounted on the lower ends of the bars 17 are shoes 19 which are slidable on the side bars 11 of the frame 10 in the guides 12 for slidably connecting said bars 17 to said frame.

Extending between the bars 18 is a fixed rod 20 having mounted thereon guides 21 the purpose of which will be presently set forth. The rod 20 passes through slots 22 which are provided therefor in the bars 17. Thus, the bars 17 and 18 are operatively connected. An adjusting rod 23 is connected to the lower portions of the bars 17. The rod 23 extends slidably through an opening provided therefor in the cross member 13 of the frame 10 and has threaded thereon an adjusting nut 24.

Journalled on the fixed shaft or rod 20 is a pneumatic tire equipped driven wheel 25. As best seen in Fig. 2 of the drawings, the wheel 25 is engaged between the outer portions of the wheels 15 in a manner to be frictionally driven thereby. Mounted for vertical sliding movement in the guides 21 is a stem or rod 26. Rotatably mounted on the upper end of the rod 26 is a horizontal spreading disk 27. The reference numeral 28 designates a suitable bearing for the disk 27 on

the rod 26. The bottom of the spreading disk 27 is frictionally engaged with the periphery of the wheel 25 for actuation thereby. This frictional contact is maintained at all times through the medium of a coil spring 29 on the lower portion of the rod 26. Of course, the spreading disk 27 is located beneath the discharge opening 7 for receiving the material from the hopper 1. Extending upwardly from the spreading disk 27 through the opening 7 is an agitator 30 which is operable in the lower portion of the hopper 1.

Hingedly mounted for swinging adjustment in a vertical plane beneath the inclined side portions 5 of the hopper 1 is a pair of baffles 31 for controlling the width of the area over which the material will be spread. Chains 32 are provided for adjusting the baffles 31.

It is thought that the operation of the device will be readily apparent from a consideration of the foregoing. Of course, the hopper 1 receives the material to be spread from the truck body 2. As the machine travels over the ground behind the truck the wheels 15 are rotated. Thus, the wheel 25 is driven which, in turn, rotates the disk 27. With the slidable closure plates 8 open and in the desired adjusted position, the material from the hopper 1 flows by gravity through the discharge opening 7 and drops onto the rotating disk 27. As will be readily seen, this material is thrown from the disk 27 by centrifugal force. The construction and arrangement is such that a uniform or even spread of the material is had. As hereinbefore stated, by adjusting the baffles 31 the width of the spread may be controlled. To adjust the wheels 15 relative to the hopper 1 for different heights of trucks the lazy tong device 16 is opened or closed through the medium of the rod 23. The bars 18 swings on the axes of the wheels 15, and therefore, the driven wheel 25 is always in contact with said wheels 15.

It is believed that the many advantages of a material spreader constructed in accordance with the present invention will be readily understood and although a preferred embodiment of the machine is as illustrated and described, it is to be understood that changes in the details of construction and in the combination and ar-

rangement of parts may be resorted to which will fall within the scope of the invention as claimed.

What is claimed is:

1. A material spreader of the class described comprising a frame, a ground engaging wheel rotatably mounted on said frame, a lazy tong device mounted on the frame, a hopper mounted on said lazy tong device, means for actuating the lazy tong device for adjusting the hopper and the ground engaging wheel relative to each other, a spreading disk rotatably mounted beneath the hopper for receiving material therefrom, and means for actuating said spreading disk. 5

2. A material spreader of the class described comprising a frame, a ground engaging wheel rotatably mounted on said frame, a lazy tong device mounted on the frame, a hopper mounted on said lazy tong device, means for actuating the lazy tong device for adjusting the hopper and the ground engaging wheel relative to each other, a spreading disk rotatably mounted beneath the hopper for receiving material therefrom, and means for actuating said spreading disk, the last named means including a wheel rotatably mounted on the lazy tong device and 10 frictionally engaged with the first named wheel and with the spreading disk. 15

3. A material spreader of the class described comprising a frame, a pair of spaced ground engaging wheels rotatably mounted in said frame, a lazy tong device mounted on the frame, a hopper mounted on said lazy tong device, means for actuating the lazy tong device for adjusting the hopper and the frame relative to each other, a rod mounted for vertical sliding movement on 30 the lazy tong device, a spreading disk rotatably mounted on said rod and located beneath the hopper for receiving material therefrom, a wheel rotatably mounted on the lazy tong device and 35 engaged with the first named wheels for actuation thereby, the second named wheel also being engaged with the spreading disk for frictionally driving same, and resilient means operatively connected to the vertically slid able rod for engaging the spreading disk with the second named wheel. 40 45
